(57) **CLAIM**

The ornamental design for a suspended light fixture, as shown and described.

DESCRIPTION

FIG. 1 is an isometric view of the suspended light fixture; FIG. 2 is a bottom plan view of the suspended light fixture; FIG. 3 is a top plan view of the suspended light fixture; FIG. 4 is a front side elevation of the suspended light fixture, a back side elevation, a left side elevation and a right side elevation being mirror images thereof;

FIG. 5 is an isometric view of the suspended light fixture and additional structure that forms no part of the claimed design; FIG. 6 is a bottom plan view of the suspended light fixture and additional structure that forms no part of the claimed design;

FIG. 7 is a top plan view of the suspended light fixture and additional structure that forms no part of the claimed design; FIG. 8 is a front side elevation of the suspended light fixture, and additional structure that forms no part of the claimed design, a back side elevation being a mirror image thereof;

FIG. 9 is a left side elevation of the suspended light fixture, and additional structure that forms no part of the claimed design, a right side elevation being a mirror image thereof. Portions or features of the light fixture not shown in the drawings form no part of the claimed design. In FIGS. 1, 3, 4, 5 and 7, heavy broken lines indicate a boundary between the claimed design and unclaimed regions. In FIGS. 5-9, light broken lines indicate portions of the suspended light fixture that form no part of the claimed design.

The patches of broken cross-hatching shown in FIGS. 1-9 are representative of possible visible texturing and are shown in broken lines so as to form no part of the claimed design.
